UNITED STATES PATENT OFFICE.

JOHN STOCKFLETH, OF CROCKETT, CALIFORNIA.

CONCRETE PILING.

Application filed April 5, 1921. Serial No. 458,790.

To all whom it may concern:

Be it known that I, JOHN STOCKFLETH, a citizen of the United States, residing at Crockett, in the county of Contra Costa and State of California, have invented new and useful Improvements in Concrete Piling, of which the following is a specification.

This invention relates to sheet piling construction, and particularly pertains to structures of the class shown and described in my Patent No. 1,371,709, dated March 15, 1921.

It is the principal object of the present invention to provide sheet piling which are preferably made of cementitious material and which are so constructed as to be readily driven and combined to form suitable piling structures, such as cofferdams and the like; the elements of the present invention being so designed as to make it possible to readily match up the various piles and to create water-tight joints therebetween.

The present invention contemplates the use of a plurality of starting piles, having wings, the edges of which are formed with longitudinal, interlocking joint members adapted to cooperate with complementary members of sheet piling and, when driven alongside thereof, to permit a water-tight joint to be formed therebetween.

The invention is illustrated by way of example in the accompanying drawing, in which—

Fig. 1 is a view in perspective, showing a section of a piling structure embodying the elements of the present invention and with parts broken away for the sake of convenience.

Fig. 2 is an enlarged view in plan, showing the sheet piling formed stave-shaped for use in circular dams.

Fig. 3 is an enlarged fragmentary view of the lower end of several of the sheet piles with parts broken away, showing two means by which the packing groove between the piling joints may be closed.

Fig. 4 is a view in transverse section through a joint, as seen on the line 4—4 of Fig. 3.

Referring more particularly to the drawing, 10 indicates a starting pile. This pile is formed with a body portion substantially rectangular in section and from the four vertical faces of which wings 11 extend. These wings are arranged at right angles to each other and their vertical edges are

provided to form one element of an interlocking joint, the other element of which is supplied by an abutting vertical edge of the sheet piling 12. The vertical joints are substantially in the form of tongues and grooves, although it is to be understood that the wings are not all formed with a single one of these elements, but may be constructed with an assortment of tongues and grooves upon the various elements, as, for example, in Fig. 1 three of the wings are provided with tongues 13 and one wing with a groove 14. Variations of this arrangement might be made without departing from the spirit of the invention.

The tongues are substantially semicircular in section and are of a width slightly less than the width of the wing, thereby forming a shoulder 15 at each side of the curved face of the tongue. Extending downwardly along the outer edge of each of the tongues is a semicircular packing groove 16. In some instances this groove extends the entire length of the tongue while in other cases it is discontinued in the manner and for a purpose which will be herein-after set forth.

The arcuate tongues are adapted to mesh with arcuate grooves 14 which may be formed along the wings of the starting piling or along the edges of the sheet piling. These grooved members are of less depth than the corresponding tongues, thereby causing a slight space 17 to occur between adjacent shoulders 15 of the abutting members. The sheet piling is substantially rectangular in section, with the exception of the difference in configuration, formed by the longitudinally extending tongue and groove members along the opposite edges thereof and the width of the sheet piling is preferably equal to the width of the wings of the starting pile.

In order to properly drive the sheet piling and to insure that it will hug against the wing of the starting pile, the lower ends of the sheet piling are chamfered, as indicated at 18. This bevel is upon the opposite side of the piling from the piling element against which it is being driven and will, therefore, tend to wedge the piling in at its lower end during the driving operation and insure that a tight joint will be produced between the tongue and groove members of the adjacent edges of the piling.

It may be desirable to provide driving ex-

tensions 19 at the top of the starting and sheet piling so that pressure may be exerted thereagainst without danger of shattering the main body of the elements. During the 5 driving operation it is also desirable to place a swab 20 within the recessed packing groove 16, as shown in Fig. 1. This will prevent pieces of cement and other bodies from falling into the packing grooves and 10 clogging the same so that packing material cannot be forced therealong.

In some instances it is not necessary to pack the joint between the piling members for their full length as the lower ends of the 15 members will be driven below the water line. For that reason a construction, indicated in Figs. 3 and 4, is provided. This consists in a filled-in portion 21, at the bottom of the packing groove 16 on the tongue member of 20 a piling and a complementary filled-in portion 22 at the bottom of the packing groove of the groove member of the piling. These members have complementary arcuate faces forming continuations of the surfaces of 25 the tongue and grooves along the edges of the piling, thus making it possible for the piling to rotate along their joints as provided by the slight spacing between the shoulders 15 without cracking or otherwise 30 damaging the edges of the abutting piling. It will be understood that the filled-in portions 21 and 22 may extend for any desired length and as it is intended to precase these piles, the lengths will necessarily be determined before the piles are driven.

In the form of the invention shown at the left-hand side of Fig. 3, a swab member 23 is secured to a bracket 24 embedded within the edge of a pile. This swab is carried down as the pile is driven and will clear the packing joint grooves, at the same time filling the same at the lower end.

In some cases it may be desirable to form a piling structure on the arc of a circle, in 45 which instance the sheet pile staves 25 are provided. As shown in Fig. 2, these members are each formed with a tongue and groove along their opposite vertical edges, and it is to be understood that other arrangements could be made, the same as indicated in the straight sheet piling of Fig. 1 where certain of the piling are formed; one with longitudinal tongues and grooves along their opposite edges; another with 55 grooves along both edges; and another with tongues along both edges. Due to this arrangement it is possible to make any sort of joint required and to insure that the sheet piling will match as they are driven along and between the various starting piling.

In the operation of the present invention, it is first intended to drive the starting piling, after which sheet piling may be driven against the wings thereof. During the driving operation the swab 20 is positioned with-

in the packing grooves of the adjacent piling joints, and the piling may be selected with permanently closed lower ends, as shown in Figs. 3 and 4, or the swab closed lower end, as shown in Fig. 3. After the piling has 70 been driven the swabs 20 are removed and the longitudinal packing openings 26 are then filled with a suitable packing material.

If desired, the various piling elements may be fastened together by irons 27. It will 75 thus be seen that by the use of piling of the construction here disclosed, it is possible to readily form and drive a desired length of piling and to insure that water-tight joints 80 may be produced therebetween.

While I have shown the preferred form of my invention as now known to me, it will be understood that various changes may be made in the combination, construction and arrangement of parts by those skilled in the 85 art without departing from the spirit of the invention as claimed.

Having thus described my invention, what I claim and desire to secure by Letters Patent is—

1. In a plastic sheet pile construction, a starting pile having a central portion from which a plurality of wings project, certain of said wings being formed with a longitudinally extending groove along their outer edges and certain of said wings being formed with a longitudinally extending tongue along their outer edges.

2. In a plastic sheet piling construction, a concrete starting pile having a square, central body longitudinally extending wings formed upon the opposite sides of said body and extending at right angles to each other, the outer edges of said wings being formed with longitudinal tongues and grooves and 105 the lower ends of said wings being chamfered to facilitate in driving.

3. In a plastic sheet piling construction, a concrete starting pile having a plurality of longitudinal wings extending from the sides 110 thereof, joint elements formed along the outer longitudinal edges of said wings, said elements comprising separate tongues and grooves, one being arranged upon each of the wings, and a longitudinal packing 115 groove extending down the central face of the joint tongues and grooves.

4. In a plastic sheet piling construction, a concrete starting pile having a plurality of longitudinal wings extending from the sides thereof, joint elements formed along the outer longitudinal edges of said wings, said elements comprising separate tongues and grooves, one being arranged upon each of the wings, and a longitudinal packing 125 groove extending down the central face of the joint tongues and grooves, the lower ends of said joint members being chamfered.

5. In a concrete piling construction, a pil- 130 ing made substantially rectangular in shape

and having joint elements formed along the opposite edges thereof, said elements having longitudinally extending tongues and grooves, and a packing groove extending centrally and longitudinally of each of said joint faces.

6. In a concrete piling construction, a piling made substantially rectangular in shape and having joint elements formed along the opposite edges thereof, said elements having longitudinally extending tongues and grooves, and a packing groove extending centrally and longitudinally of each of said joint faces, one of said joint faces being 15 chamfered at its lower end.

7. In a sheet piling construction, a concrete starting pile having a longitudinally extending body portion, a plurality of wings extending therefrom, certain of said wings 20 having a joint recess extending the length of the outer edges thereof and other of said wings having a tongue extending the length of the outer edges thereof, the tongues and grooves being formed with centrally disposed, longitudinally extending packing recesses, and sheet piling adapted to be driven alongside said starting piling and with one edge abutting against the edge of a starting pile wing, said abutting edge being 25 formed with a complementary joint member to that occurring along the wing of the starting pile whereby a longitudinal packing passageway will be formed between the piling and throughout the length thereof.

30 8. In a sheet piling construction, a concrete starting pile having a longitudinally extending body portion, a plurality of wings extending therefrom, certain of said wings having a joint recess extending the length 35 of the outer edges thereof and other of said wings having a tongue extending the length of the outer edges thereof, the tongues and grooves being formed with centrally disposed, longitudinally extending packing recesses, sheet piling adapted to be driven alongside said starting piling and with one edge abutting against the edge of a starting pile wing, said abutting edge being formed 40 with a complementary joint member to that occurring along the wing of the starting pile whereby a longitudinal packing passageway will be formed between the piling and 45

50 throughout the length thereof, and a swab member for closing the lower end of said packing opening.

55 9. In a plastic sheet pile construction, a starting pile having a plurality of extending wings, a projecting tongue being formed longitudinally of the outer vertical edges of said wings.

60 10. In a plastic sheet pile construction, a starting pile having a plurality of extending wings, a projecting tongue being formed longitudinally of the outer vertical edges of said wings, and a series of plastic sheet piles 65 adapted to be driven in alignment with the wings of the said starting pile, the edges of the piling abutting and a complementary groove being formed along the abutting edges of the sheet piles.

70 11. In a plastic sheet pile construction, a starting pile formed of concrete having a central body provided with a plurality of wings extending longitudinally thereof and projecting at right angles to one another, 75 each wing being formed with a tongue on its longitudinal edge, the said main body portion extending above the wings at one end to form a driving head.

80 12. In a plastic sheet pile construction, a starting pile formed of concrete having a central body formed with a plurality of wings extending therefrom at right angles to each other, one or more of the wings being formed with a tongue along the longitudinal edge and one or more of the wings being formed with a groove along the longitudinal edge.

85 13. In a plastic sheet pile construction, a starting pile formed of concrete having a central body formed with a plurality of wings extending therefrom at right angles to each other, one or more of the wings being formed with a tongue along the longitudinal edge and one or more of the wings being formed with a groove along the longitudinal edge, and plastic sheet piles adapted to be driven in alignment with the wings of the starting pile, each of the sheet piles being 90 formed with a longitudinal edge complementary to the edge of the wing adjacent which it is driven.

95 JOHN STOCKFLETH.
